Patented Dec. 30, 1975

238,249

BOTTLE CARRIER

Gerald Erickson, P.O. Box 6175,
Surfside, Fla. 33154

Filed May 22, 1974, Ser. No. 472,089

Term of patent 14 years

Int. Cl. D9—99

U.S. Cl. D9—178

FIG. 1

FIG. 2

FIG. 3

FIG. 4

FIG. 5

FIG. 1 is a plan view of a bottle carrier embodying my new design;

FIG. 2 is a bottom view;

FIG. 3 is a view taken along the line of 3—3 of FIG. 1 looking in the direction of the arrows;

FIG. 4 is an end view; and

FIG. 5 is a view taken along the line 5—5 of FIG. 1 looking in the direction of the arrows.

I claim:

The ornamental design for a bottle carrier, as shown.
